[57] CLAIM

The ornamental design for a tub strainer wrench with
multi-positionable handle, as shown and described.

DESCRIPTION

FIG. 1 is a one end perspective view of the tub strainer
wrench with multi-positionable handle showing my
new design;

FIG. 2 is an opposite end perspective view thereof, with
the handle shown in the alternate position;

FIG. 3 is an enlarged end elevational view thereof, with
the handle shown removed for ease of illustration only;

FIG. 4 is an enlarged opposite end elevational view
thereof, with the handle shown removed for ease of
illustration only; and

FIG. 5 is an enlarged side elevational view thereof, with
the handle shown removed for ease of illustration only.

FIG. 1

FIG. 2

FIG. 3

FIG. 5

FIG. 4
